US00D895901S

(12) **United States Design Patent** (10) **Patent No.:** **US D895,901 S**
(45) **Date of Patent:** ** *Sep. 8, 2020

(54) **HEARING PROTECTOR**

(71) Applicant: **3M INNOVATIVE PROPERTIES COMPANY**, St. Paul, MN (US)

(72) Inventors: **Robert C. Coffin**, Zionsville, IN (US); **Matthew V. Stonebraker, Jr.**, Lafayette, IN (US); **Jacob H. Ely**, Indianapolis, IN (US); **Ravi Thomas**, Avon, IN (US)

(73) Assignee: **3M Innovative Properties Company**, St. Paul, MN (US)

(*) Notice: This patent is subject to a terminal disclaimer.

(**) Term: **15 Years**

(21) Appl. No.: **29/616,041**

(22) Filed: **Sep. 1, 2017**

(51) LOC (12) Cl. **29-02**

(52) U.S. Cl.

(57) **CLAIM**

The ornamental design for a hearing protector, as shown and described.

DESCRIPTION

FIG. 1 is a perspective view of a first embodiment of a hearing protector showing our new design;

FIG. 2 is a front view thereof;

FIG. 3 is a back view thereof;

FIG. 4 is a top view thereof;

FIG. 5 is a bottom view thereof;

FIG. 6 is a perspective view of a second embodiment of a hearing protector showing our new design;

FIG. 7 is a front view thereof;

FIG. 8 is a back view thereof;

FIG. 9 is a top view thereof; and,

FIG. 10 is a bottom view thereof.

The broken lines shown in the drawings represent portions of the hearing protector that form no part of the claimed design.

1 Claim, 4 Drawing Sheets
